(57) **CLAIM**

The ornamental design for a sponge holder, as shown and described.

DESCRIPTION

FIG. 1 is a front perspective view of a sponge holder design showing my new design.

FIG. 2 is a rear perspective view of a sponge holder.

FIG. 3 is a front view of a sponge holder.

FIG. 4 is a rear view of a sponge holder.

FIG. 5 is a left side view of a sponge holder.

FIG. 6 is a right side view of a sponge holder.

FIG. 7 is a top view of a sponge holder; and,

FIG. 8 is a bottom view of a sponge holder.

Any shading and cross-hatching are not features of the design but are utilized to illustrate the surface contours of the sponge holder design in the drawings.
